CLAIM

The ornamental design for a plunger, as shown and described.

DESCRIPTION

FIG. 1 is a diagrammatic perspective view of the plunger in full lines with a drain and hands shown in broken lines representing environmental association matter being for illustrative purposes only and forming no part of the claimed invention.

FIG. 2 is a front elevational view thereof, the rear, left and right side elevational views being mirror images of the front view;

FIG. 3 is a top plan view of the plunger; and,

FIG. 4 is a bottom plan view thereof.
